CLAIM

The ornamental design for a box, as shown and described.

DESCRIPTION

FIG. 1 is a perspective view of a box showing my new design;

FIG. 2 is a top plan view thereof;

FIG. 3 is a front elevational view thereof;

FIG. 4 is a left side elevational view thereof, the right side elevational view being a mirror image thereof; and, FIG. 5 is a rear elevational view thereof.

The broken lines are intended to show fold lines. The bottom is plane and unornamented.

FIG. 1

FIG. 2

FIG. 5

FIG. 4

FIG. 3
